TOY TRACTOR FOR WHEELED VEHICLES

Allan J. Alvaney, Arlington Heights, Ill., assignor to Sears, Roebuck and Co., Chicago, Ill., a corporation of
New York

Filed Oct. 28, 1960, Ser. No. 62,653

Term of patent 3½ years

(Cl. D34—15)

FIG. 1 is a perspective view of a toy tractor for wheeled vehicles showing my new design,

FIG. 2 is a fragmentary side elevational view of the same, showing the side opposite that seen in FIG. 1, the part broken away being substantially similar to the rear portion seen in FIG. 1,

FIG. 3 is a front elevational view thereof, and

FIG. 4 is a rear elevational view of the same.

I claim:

The ornamental design for a toy tractor for wheeled vehicles, substantially as shown and described.
